Patented June 9, 1925.

UNITED STATES PATENT OFFICE.

ERSKINE POLK HARLEY, OF OKLAHOMA CITY, OKLAHOMA.

COOL CUSHION AND SEAT.

Application filed June 27, 1922. Serial No. 571,132.

To all whom it may concern:

Be it known that ERSKINE POLK HARLEY, a citizen of the United States, residing at Oklahoma City, in the county of Oklahoma and State of Oklahoma, has invented 5 certain new and useful Improvements in Cool Cushions and Seats, of which the following is a specification.

My invention relates to cushions and has 10 for one of its objects, a cushion to be superimposed upon a seat, chair or other support and upon which the body of a person may rest and which will maintain a predetermined air space between the body and the 15 seat or other support. The air space permits a circulation of air between the body and the seat or support.

Another object of my invention is to produce a device which is flexible and which 20 will readily conform to the shape of the body and at the same time maintain the air space between the body and seat or support above referred to.

Another object of my invention is to provide 25 a structure which is porous and thereby allows air from without the cushion to replace that within the cushion through such portions of the cushion as are not closed by the body of the person seated thereon, and 30 at the same time allow the air circulating within the cushion to contact with the clothing of a person seated upon the cushion.

Another object of my invention is to produce 35 a structure which will permit the body of the person seated thereon to move relative to the seat or other support without relative movement of the body and seat or relative movement of the seat and support, thereby eliminating wear upon the clothing 40 or upon the support, which may be very objectionable if the support is covered with fabric subject to wear and at the same time such movement is much less annoying to a person seated thereon.

45 Further objects will be disclosed herein-after.

My invention resides in the new and novel construction, arrangement and combination of the parts hereinafter fully described and 50 shown in the drawings.

In the drawings accompanying this specification:

Figure 1 shows my invention comprising 55 a seat and back portion flexibly hinged together.

Fig. 2 is an enlarged view in part of

Fig. 1 to show clearly the details of construction.

Fig. 3 is a modification as relates to a detail in construction giving stability to 60 the device.

My invention comprises two portions; namely, a back and seat portion A and B respectively. Each portion A and B comprises a spirally wound coil spring F usually made of small steel wire with the coils of the spring substantially vertically disposed with respect to the plane of the section A or B and may be spaced apart to 65 form a supporting structure which will permit the free circulation of air through the member F, to give the proper strength to support the body, and in which the convolutions are free to move relative to each other in order to conform readily 70 to the body and give flexibility and cushioning effect to the structure. The convolutions of the member F reside substantially in a common flat plane except when forced 75 out of such plane by pressure from without. 80 The forming of the convoluted member F usually starts at the center and the coil spring is wound upon itself about a common axis which forms the center of the section A or B, and until the proper number of 85 convolutions is secured to give the diameter required.

In order to prevent each section from buckling and to cause it to maintain its shape and the back to stand up, I employ 90 an outer member G to stiffen the periphery of each section to a sufficient degree to give stability to each section, but not to be unyielding to the extent of inconveniencing the person seated. The member G, which 95 I will term a rim, as shown in Fig. 2 is a spirally wound member similar to that of member F, but may be composed of a wire of larger diameter and wound much closer than the member F. The yielding member 100 F maintains an air space between the body and the support and the member G stiffens and gives stability to the structure.

A modification of the member G is shown in Fig. 3 and comprises a coiled member L 105 similar to that of F enclosing the ring M usually of flexible metal.

If the article is to comprise a seat and back section, two convoluted members F and G are prepared and assembled as shown 110 in Fig. 2 or the members F, L and M are assembled as shown in Fig. 3, and these are

covered on both faces with one or more layers of fabric cut to the desired shape and of such size as to form a continuous covering for the two portions A and B, that is, at the flexible joint between the sections A and B the covering is continuous. I prefer to use two superimposed layers D and E.

In order to strengthen that portion of the members D and E between the sections, I apply to the outer face of the front and back portions of the covering, and along that portion where the sections are being bent back and forth, a strip of heavy webbing H stitched in place as indicated at C.

15 The members D and E on the front and back of each section are stitched around the edge outside of the rim G and close thereto. A webbing I is then applied to the outer raw edge of the members D and E and stitched thereto as shown. The webbings I and H are also stitched together as indicated.

15 The members D and E I prefer to make of a coarsely woven fabric and may be of 25 various materials, as for instance, it may be woven from paper yarn which, I find, is tough, absorbent and will resist wear, or it may be of cotton or woolen yarn.

In order to give shape to the binding edge 30 I and maintain its shape and also to add a slight stiffness to the binding edge I, I insert therein a small wire member J which I prefer to make of steel or phosphor bronze wire possessing resiliency. This member J is not continuous across the line of flexure between the back and seat portions.

If the sections are made separate for use 35 as a seat or back only and which are convenient for use on stools and as porch seats, a similar construction will be carried out as 40 described above and will be apparent to one skilled in the art, and where the sections are separate they will usually be shaped

round although my method of construction lends itself readily to other shapes.

In order to keep the back section in place when in use, I detachably secure to one of the sections a tab K provided with button holes K' whereby the tab may be secured to a button secured to the main seat or support. The tab K is also convenient in maintaining the sections in a completely folded relation for convenience in carrying, as the tab can be brought around and over the edge of the two folded sections and secured to the opposite section by means of a button secured thereto as will be evident.

I claim:

1. An article of manufacture comprising an enclosed member, a convoluted member 60 within the enclosing member to hold the enclosing member distended and means separate and independent of the convoluted member circumscribing the convoluted member within the enclosing member to give 65 stability to the structure.

2. An article of manufacture comprising an enclosing member, a convoluted member within the enclosing member to hold the enclosing member distended to permit free 70 circulation of air therein and means separate and independent of the convoluted member, circumscribing the convoluted member to give stability to the structure.

3. An article of manufacture comprising 75 an enclosure of a plurality of fabric members, means for holding the enclosure distended and allow free circulation of air therein and means comprising a separately formed and independent ring circumscribing the holding means for giving stability to the structure.

In testimony whereof I affix my signature.

ERSKINE POLK HARLEY.
